UNITED STATES PATENT OFFICE.

JOSEPH N. WIGGIN, OF EAST ORANGE, NEW JERSEY, ASSIGNOR TO H. B. WIGGIN'S SONS COMPANY, OF BLOOMFIELD, NEW JERSEY, A CORPORATION OF NEW JERSEY.

DESIGN FOR FABRIC OR PAPER FOR COVERING WALLS OR BOOK-COVERS.

41,572.

Specification for Design.

Patented July 11, 1911.

Application filed February 4, 1911. Serial No. 606,653. Term of patent 14 years.

To all whom it may concern:

Be it known that I, JOSEPH N. WIGGIN, a citizen of the United States, residing at East Orange, in the county of Essex and State of New Jersey, have invented a new, original, and ornamental Design for a Fabric or Paper for Covering Walls and Book-Covers, of which the following is a specification, reference being had to the accompanying drawings, forming a part thereof, in which the figure is a plan view of a portion of a wall covering showing my new design.

I claim:

The ornamental design for a fabric or paper for covering walls and book covers.

JOSEPH N. WIGGIN.
